DESIGN FOR A TOY SANDBOX

Edward Gerstell McCandlish, Van Wert, Ohio

Application December 27, 1938, Serial No. 82,007

Term of patent 14 years

To all whom it may concern:

Be it known that I, Edward Gerstell McCandlish, a citizen of the United States, residing at Van Wert, in the county of Van Wert and State of Ohio, have invented a new, original, and ornamental Design for a Toy Sandbox, of which the following is a specification, reference being had to the accompanying drawing, forming part thereof.

Fig. 1 is a side perspective view of a toy sandbox, showing my new design.

Fig. 2 is a top plan view thereof on a slightly reduced scale; and

Fig. 3 is a bottom plan view on a reduced scale. The opposite side of the sail is plain and unornamented.

I claim:

The ornamental design for a toy sandbox, as shown and described.

EDWARD GERSTELL McCANDLISH.
